COATING APPARATUS

William C. Huebner, New York, N. Y.

Application September 22, 1936, Serial No. 101,951
Renewed August 13, 1938

2 Claims. (Cl. 91—18)

This invention relates to improvements in coating apparatus and, more particularly, apparatus for coating cylinders such as rotogravure cylinders and inking cylinders with coatings, emulsions and inks.

One object of the invention is to provide an efficient apparatus for depositing liquid coatings of widely variable characteristics, uniformly on the surfaces of relatively large cylinders.

Another object of the invention is to provide an apparatus for applying liquid coatings to the surfaces of cylinders in the form of thin sheets or layers of desired width corresponding to the lengths of the cylinders and of an adjustable thickness dependent upon the nature and consistency of the coating material and its intended use.

More specific objects of the invention are to provide a coating apparatus of the character indicated in the preceding paragraphs wherein provision is made for accelerating the drying or setting of the applied coating; for maintaining the coating material at the desired temperature and consistency for proper and rapid application; and for applying pressure to the coating material during the application thereof to the cylinder surfaces in those instances where the coating material is of a thick and more or less semi-plastic nature.

Other objects of the invention will more clearly appear from the description and claims hereinafter following.

In the drawings forming a part of this specification, Figure 1 is a front elevational view of a machine or apparatus having the improvements incorporated therein. Figure 2 is a vertical transverse sectional view, upon a somewhat enlarged scale, corresponding to the section line *x—x* of Figure 1, parts being broken away at the bottom to better accommodate the view on the sheet. And Figure 3 is a longitudinal, horizontal sectional view, upon an enlarged scale, corresponding substantially to the section line *y—y* of Figure 1.

In said drawings, the apparatus comprises broadly a base A; a horizontally reciprocating carriage B; a tank or container for the coating solution or other material to be applied to the surface of the cylinder D. Various other features of the invention are described in detail hereinafter.

The base A will preferably be built up of channels 20 having mounted thereon along each side thereof, tracks 24, which overhang the channels 20 for the purpose hereinafter described.

The carriage B preferably includes a bottom casting 26 extending the full length thereof and with which is rigidly or fixedly associated at one end thereof, a vertically extending heavy standard 27, said standard being at the right hand end,

as viewed in Figure 1. Slidably mounted on said bottom casting 26 at the opposite end thereof, is a second vertically extending standard 28. A plurality of combined bracings and guide rods 29—29, preferably four in number, as best shown in Figure 2, are employed, the same being rigidly connected at their right hand ends, as viewed in Figure 1, to the standard 27 and slidably connected, at their opposite ends, with the standard 28 and adapted to be locked or secured in adjusted position with reference to the standard 28 by set screws 50 threaded into the standard 28 in line with the rods 29. By this construction, it will be evident that the carriage B is adjustable as to length to thereby accommodate cylinders D of varying length.

To provide for reciprocatory movement of the carriage B, the latter is supported on the tracks 24 by a plurality of antifriction rollers 31 and, to prevent upward tilting or displacement of the carriage B, additional anti-friction rollers 32 are provided, the latter being carried by the brackets secured to the base casting 26 and the rollers being disposed beneath the overhanging portions of the tracks 24. Reciprocatory movement is imparted to the carriage B as by the motor 33 mounted on a cross plate 23 in the base A, said motor, through suitable worm gearing, driving a disk 38 having radially adjustably connected thereto, a pitman 41 which in turn is pivotally connected as indicated at 32 to the bottom casting 26 of the carriage. With the construction broadly indicated, it is evident that a rapid reciprocatory movement of desired length of stroke may be imparted to the carriage B. The parts of the base carriage and reciprocating drive, so far referred to, are or may be the same as those described in my copending application, Serial Number 99,447, filed Sept. 4, 1936, for improvement in Coating machines, to which reference may be had for a more detailed description.

As previously indicated, the standard 28 is adjustable toward and from the standard 27 to accommodate cylinders of different length and the means for effecting such adjustment preferably consist of racks 44 provided along the undersides of the rods 29 and with which racks cooperate pinions 45—45 carried on transversely extending shafts 46—46. The upper shaft 46, as shown in Figure 2, is provided with a crank handle 47 and, to insure simultaneous and equal rotation of all of the pinions 45, the shafts 46 have secured thereto sprocket gears 48 over which extends a sprocket chain 49. The carriage length adjusting means just described are similar to those disclosed in my said copending application to which reference may be had for a more detailed description.

To rotatably support the cylinder D through its trunnions 68, the carriage B has vertically

slidably mounted on the outer side of each of the standards 27 and 28 thereof, a cross head 56, vertical adjustment being effected through nuts 57 on the cross head with which cooperate adjusting screws 58. The screws 58 are swivelled in brackets 59 secured to the standards 27 and 28 and are adapted to be simultaneously actuated through helical gears 60 carried by a longitudinally extending shaft 63, all as more particularly described in my said copending application. The cross heads 56, at their upper ends, are provided with pairs of heavy anti-friction rollers 61 which provide two rolling points of supports for each of the trunnions 68 as will be understood.

15   Rotary motion is imparted to the cylinder D from a motor 87 vertically adjustably mounted on an extension bracket 156 carried by the left hand cross head 57, as viewed in Figure 1. The shaft of the motor 87 carries a V-pulley with 20 which cooperates a V-belt 89, the latter taking over a V pulley 90 adapted to be temporarily rigidly secured to the adjacent trunnion 68 of the cylinder by any suitable means such as an expandible mandrel such as shown and described 25 in my said copending application.

From the preceding description, considered in connection with the more detailed disclosure of my copending application, Serial No. 99,447, it will be apparent that the entire carriage B may 30 be given a reciprocatory movement carrying the cylinder D therewith and also rotary movement imparted to the cylinder D either simultaneously or alternately as conditions may require, dependent upon the nature of the coating to be applied 35 to the cylinder.

Referring now more particularly to Figures 2 and 3 and the tank or container C. The carriage B, at its upper end, is provided with horizontally extending heavy tracks 120, each secured to the standards 27 and 28, respectively, and slidably mounted on said tracks, toward and from the cylinder D, are castings 121 which support the tank or container proper C. Horizontal adjustment is effected through racks 122 secured to the inner sides of the tracks 120 and pinions 123 carried by a shaft 124 journaled at its ends in the castings 121. Said shaft 124 is adapted to be operated by a crank arm 125.

The tank C is of special construction, having vertical end walls 126-126, a diagonally extending partition 127 and fixed bottom wall 128, said end and bottom walls and partition 127 being rigidly united. The front wall of the material containing chamber 129, is formed by a vertically adjustable slide 130 mounted in the guides 131 formed in the end walls 126, as shown in Figure 3.

Disposed above the partition 127 and held in spaced relation with respect thereto by spacer blocks 132 is a second inclined partition 133 forming the true bottom of the chamber 129. Said partition 133 has its lower end extended downwardly toward the cylinder surface with a beveled edge 134 which normally will be placed 65 closely adjacent the surface of the cylinder so as to effect delivery of the coating material in a thin sheet, as indicated at 135, onto the surface of the cylinder rotated in the direction indicated by the arrow a. As will be apparent from Figure 2, the coating material is delivered or deposited upon the cylinder surface in a line above a horizontal plane passing through the axis of the cylinder. The desired thickness of the sheet of coating material as delivered from the tank C is obtained by adjusting the front wall 130 of

the tank, the latter having a lower beveled edge 136 parallel to the partition 133.

Adjustment of the front wall 130 of the tank is effected through the following means. Said wall 130 is provided with an outer spaced wall 137 held in spaced relation by spacer blocks 1 to provide a liquid chamber 139 for the purpose hereinafter described. Secured to said front wall 137, at each end thereof, and on the outside, are vertical racks 140 with which cooperate pinions 141-141 carried by a horizontally extending shaft 142 journaled in brackets 143-143 in turn rigidly mounted on the end walls 11 of the tank. At one end thereof, the shaft 14 carries a worm gear 144 with which cooperates a worm 145 carried by a vertically disposed shaft 146 journaled in an extension 147 of the bracket 143, said shaft 146 being provided with a crank arm 148 at the top thereof. As will be apparent the valve control front wall 130 can be delicately adjusted through the worm bearing described an its adjusted position maintained by reason of the worm gearing.

As will be evident from inspection of Figure 2, the double inclined bottom of the chamber 129 provides a second liquid containing chamber 149 and communication is established between said chamber 149 and the front liquid chamber 139 by means of pipe connections 150 and 151 the latter having a flexible unit therein such as a section of hose to accommodate the adjustment of the front wall 130.

Beneath the inclined partition 127 is formed a heating chamber 152 in which may be disposed any suitable heating means such as the electric heaters 153 indicated conventionally in Figure 2, and supplied with current through the cable 154. The chamber 152 is normally closed but rendered accessible by means of a back wall 155 in the form of a door hingedly supported at 157 and adapted to be latched at its lower edge by the latch 158.

From the preceding description, it will be seen that the coating solution within the chamber 129 may be maintained at the proper temperature and consistency, dependent upon the nature of the coating, by the heat derived from the heating element 153 and the liquid, such as water, maintained in the two intercommunicating chambers 139 and 149. To facilitate maintaining the coating solution at the desired temperature, a thermometer, as indicated at 159, may be employed, the same being mounted in the cover 160 of the tank.

In the case of certain materials to be applied to cylinder surfaces, such as heavy inks, the consistency thereof is such that the same do not flow readily under gravity. In such cases, it is desirable that the action of gravity be supplemented by pressure to insure a uniform flow and discharge of the material to the cylinder and provision is made therefor in the present invention. The cover 120 is extended beyond all sides of the tank and an air seal provided therefor by means of any suitable sealing gasket such as indicated at 161. The cover is held down securely by any suitable means as by the hinged clamping brackets 162 and screws 163 carried thereby. Air pressure is supplied from any suitable outside source as through the pipe 164 entered through the cover 160 and the desired pressure indicated through the pressure gage 165 also carried by the cover 160.

In order to control the rate of setting or drying of the coating applied to the cylinder, the

llowing arrangement is employed. Detach-
ly supported on the upper pair of bracing rods
1 and one of the lower rods 29 is a box-like
ainage tank comprising end walls 166, vertical
ick wall 167 and inclined bottom wall 168, all
idly united. The end walls are preferably
urther united and rigidified by longitudinally
tending tie rods 169.

The drainage tank is further provided with a
ont removable inclined bottom wall 170 mount-
i in suitable grooves 171 formed in the end
alls 166. The front bottom wall 170 will be so
ositioned that its lower edge 171 will be held
paced slightly from the oppositely inclined bot-
om wall 168 so as to allow drainage or discharge
f surplus material which is ultimately delivered
rom the bottom lip 172 into a V-shaped trough
73 detachably mounted on the standards 27 and
8 by any suitable means such as the hook and
lot arrangement indicated at 174. The trough
74 is provided with a drain pipe 175 to conduct
he discharge to the sewer or the like.

The drainage tank is further provided with a
ront narrow rail 176 to which is hingedly con-
ected a door closure 177 which, when in closed
osition, engages with the upper edge of the
ront bottom wall 170.

To further enclose the cylinder and complete
he drying chamber therefor, a box-like hood 178
s detachably mounted on the top of the drain-
age tank, as clearly shown in Figure 2. As will
e understood, said hood 178 will be of sufficient
ength to overlie the ends of the tank C and
rovide a practically sealed closure for the cyl-
nder except only for a sufficient opening to re-
ceive the lower extended edge of the inclined
partition 133 of the tank. In Figure 2, parts of
he hood are broken away, as indicated at 179,
merely in order to better illustrate details of
construction of the tank C.

Carried in the front wall of the hood 178 is an
exhaust fan 180 to produce a forced circulation
of air through the heating and drying chamber,
it being understood that the amount of air is
primarily regulated by the size of the slot open-
ing left between the walls 170 and 168 of the
drainage tank. As will be understood, this slot
opening may be varied in size either by provid-
ing for an adjustment of the bottom wall 170 or
by having interchangeable walls 170 of different
width.

When it is desired to accelerate the drying or
setting action by application of heat, the remov-
able bottom wall 170 may be replaced by another
similar bottom wall having on its upper side
thereof, electric heating elements such as shown
at 181 adapted to be supplied through the plug
182. Preferably, the heating elements will be
enclosed within a grill 183 so as to better diffuse
the heat. A thermometer 184 extended through
the hood 178 is preferably employed to facilitate
regulation of the temperature within the heat-
ing and drying chamber.

In actual practice, the coating material is de-
livered from the container C onto the surface
of the cylinder D while the latter is rotating in
the direction of the arrow a. As hereinbefore
described, the discharge orifice for the coating
material will be adjusted in accordance with the
characteristics of the particular coating mate-
rial which is being used. In some instances, the
coating material will be allowed to flow slowly
under the influence of gravity but in other in-
stances, where the material is relatively thick,

the container C will be sealed and air pressure
applied so as to supplement the gravity action
and force the coating material through the orifice
under increased pressure. In some cases, par-
ticularly where the coating material is relatively 5
thin and quite fluid, the entire carriage B on
which is supported the container C, will be given
a reciprocatory motion from the motor drive 38,
41, 42, in order to prevent the formation of
"beads" or "bells" of the coating material as the 10
latter is rotated and which would thereby result
in an uneven coating. As will be apparent to
those skilled in the art, the use of heat in con-
nection with the coating material in the 15
container C and the use of heat and the exhaust
fan in connection with the rotating cylinder,
will depend entirely upon the characteristics of
the coating material being used, and the speed
of drying or setting desired. In other words, the 20
apparatus is designed for a wide range of use
with provision for taking care of the many vari-
ables encountered in practical use.

From the preceding description, it will be seen
that means are provided for not only accurately
controlling the application of the coating mate-
rial to the cylinder, but also to control the rate
of drying or setting thereof after application,
thus permitting the use of the apparatus for ap- 25
plication of coating materials of widely different
characteristics.

As will be understood by those skilled in the
art, the tank C, drainage tank and associated
hood are all readily removable from the appa-
ratus to facilitate insertion and removal of the
cylinders and also to permit of interchange where 30
cylinders of different length are being coated.

Although there has herein been shown and de-
scribed what is now considered the preferred
manner of carrying out the invention, the same 40
is merely illustrative and not by way of limita-
tion, all changes and modifications being con-
templated that come within the scope of the
claims appended hereto.

What is claimed is:

1. In apparatus of the character described, the
combination with a base; of a carriage recipro-
catingly mounted on the base; means for recip-
rocating the carriage on the base; means on the
carriage for supporting and rotating a cylinder
about a horizontal axis; a material container
mounted on the carriage and disposed adjacent
the cylinder, said container having a discharge
slot orifice extending lengthwise thereof parallel
to the cylinder axis; means for applying air pres-
sure to material within the container; and heat-
ing means for the material within the container. 50

2. In apparatus of the character described, the
combination with a base; of a carriage recipro-
catingly mounted on the base; means for recip-
rocating the carriage; means on the carriage for
supporting and rotating a cylinder about a hor-
izontal axis; a material container also mounted
on the carriage; adjustable means for controlling
the discharge of material from the container to 60
a cylinder surface; a housing structure substan-
tially enclosing the cylinder, said housing struc-
ture being detachably mounted on the carriage
and including a drainage tank and a hood; and
means on said housing structure for controlling 70
the rate of drying or setting of material deposited
on the cylinder surface.

WILLIAM C. HUEBNER.
